UNITED STATES PATENT OFFICE.

CLYDE W. MATHER, OF LEONARD, COLORADO.

TOILET CASE.

Application filed May 6, 1922, Serial No. 558,959. Renewed November 24, 1923.

To all whom it may concern:

Be it known that I, CLYDE W. MATHER, a citizen of the United States, residing at Leonard, in the county of San Miguel and State of Colorado, have invented certain new and useful Improvements in Toilet Cases, of which the following is a specification, reference being had to the accompanying drawings.

10 This invention relates to improvements in toilet cases, and more particularly to a combined receptacle for a tooth-brush and paste.

An important object of the invention is 15 to provide a device of this character whereby these two articles, necessary in traveling, may be packed in a very small space, and in fact carried in the pocket after the manner of a fountain pen if so desired.

20 A further object of the invention is to provide a device of this character in which the brush portion of the device is removable for replacement.

A still further object is to provide a casing having the tooth-brush attached thereto and a cavity receiving a tube of paste, together with a cap having means for securing thereto a tube of paste for closing the end of the last named cavity.

25 These and other objects I attain by the construction and arrangement shown in the accompanying drawings wherein for the purpose of illustration is shown a preferred embodiment of my invention and wherein 30 like reference characters designate like parts throughout.

In the drawings:

Figure 1 is a longitudinal section taken 40 through a toilet case constructed in accordance with my invention;

Figure 2 is a plan view of the brush detached;

Figure 3 is a detail side elevation of a portion of the paste container;

45 Figure 4 is a sectional view showing the paste tube and container constructed separately;

Figure 5 is an enlarged detail view of the paste container tube cap; and

50 Figure 6 is a side elevation of the toilet case.

Referring now more particularly to the drawings, the numeral 10 designates a tubular casing interiorly threaded at the ends 55 thereof, as indicated at 11, and provided at

one end upon its exterior surface with screw threads 13, the purpose of which will presently appear. This casing is adapted for the reception of a tooth paste tube 14, which tube is provided at one end with the usual 60 vent cap 15, by means of which the contents may be dispensed, and at the opposite end with external screw threads 16 adapted for engagement with the internal screw threads 17 of an interiorly and exteriorly threaded 65 flange 18 formed upon the closure cap 19. The exterior threads of the flange 18 of the cap 19 engage in the threads 11 at one end of the casing 10.

The numeral 20 designates a brush section, 70 the bristles 21 of which may be of any desired degree of stiffness and the shank of which is provided with an exteriorly threaded extension 22 for engagement in the interior screw threads 12 at the other end 75 of the casing 10. This threaded portion is preferably tubular so as to permit the cap end of the paste tube 14 to seat in the shank so as to in so far as possible reduce the over all length of the completed device. The numeral 23 designates a closure cap having 80 one end closed and the opposite end provided with interior screw threads for engagement with the external screw threads 13 of the casing 10. This cap encloses the 85 brush 20 when not in use and effectually prevents the gathering of dust and the like thereon, and may be provided if so desired with an attaching clip 24 so that it may be secured within a pocket of the owner after 90 the manner of a fountain pen.

If desired, the paste tube container may be separately formed, as shown in Figure 4. In this figure the tube 10' has one end thereof closed, as indicated at 25, and the opposite end thereof interiorly screw-threaded, as at 11', the remaining construction being identical with that employed in attaching the tube in the construction above described. Such a device eliminates the necessity of carrying a tube of paste in a toilet case, suitcase or the like where it is liable to be crushed and the sticky contents thereof spread upon the remaining articles. The paste tube will be as readily removable as in the above construction and will be readily accessible when it is desired to use the same. Such separate construction is particularly well adapted for use in conjunction with a tooth-brush holder constructed in accordance with my co-pend- 110

ing application, Serial No. 558,960 filed of even date herewith for tooth-brushes.

From the foregoing it is believed to be obvious that a device constructed in accordance with my invention is particularly well adapted for the use for which it is intended by reason of the fact that the paste may be withdrawn by removing the cap, being attached to the cap itself, and accordingly will not stick or gum within the tube and be difficult to remove. It will furthermore be obvious that by separating the various portions of the device, such as the brush casing, cap and tube, these separate parts may be given a very thorough cleansing to maintain the same at all times in a sanitary condition. It will furthermore be obvious that the construction as hereinbefore set forth is capable of some change and modification without materially departing from the spirit of my invention and I accordingly do not limit myself thereto except as hereinafter claimed.

I claim:

1. In a device of the type described, and in combination, a tube, a brush removably engaged with one end of the tube, a cap enclosing the brush and engageable with the brush engaged end of the tube, a closure for the opposite end of the tube, and a dispensing tube having its base removably engaged with the closure and normally concealed within the tube, the tube engaging end of the brush being provided with a recess re-

ceiving the dispensing end of said dispensing tube.

2. A device of the type described comprising a tube interiorly screw-threaded at each end thereof and provided at one end with exterior screw-threads, a brush having a threaded shank engaged with the interior threads at one end of the tube, a cap enclosing the brush and having internal screw-threads engaged with the external screw-threads of the tube, a closure for the other end of the tube having external screw-threads engaging the internal screw-threads of the tube, and a dispensing tube removably engaged with said closure.

3. A device of the type described comprising a tube interiorly screw-threaded at each end thereof and provided at one end with exterior screw-threads, a brush having a threaded shank engaged with the interior threads at one end of the tube, a cap enclosing the brush and having internal screw-threads engaged with the external screw-threads of the tube, a closure for the other end of the tube having external screw-threads engaging the internal screw-threads of the tube, and a dispensing tube removably engaged with said closure, the shank of the brush being provided with a socket receiving the dispensing end of said dispensing tube.

In testimony whereof I hereunto affix my signature.

CLYDE W. MATHER.
